LAST FOR FOOTWEAR

Frank J. MacDonald, Brookline, Mass., assignor
to The B. F. Goodrich Company, New York,
N. Y., a corporation of New York

Application April 4, 1941, Serial No. 386,754

4 Claims. (Cl. 12—123)

This invention relates to lasts for building footwear and is especially useful where rubber soles are to be vulcanized to shoes.

The principal objects of the invention are to provide a solid support for the shoe which may be moved from one machine to another, to provide a last having relatively movable parts for effecting convenient removal of the shoe, to provide for such removal without damage to the footwear despite an easily damageable character of the same, and to provide for heating such last for vulcanizing purposes.

These and other objects will appear from the following description and the accompanying drawing.

Of the drawing:

Fig. 1 is a side elevation of the last constructed according to and embodying the invention, with a shoe thereon, the last being shown as adjusted for removing a shoe, the shoe being shown in full lines as loosened from the last but resting thereon and in dot and dash lines in an advanced position of removal, parts being broken away.

Fig. 2 is a side elevation of the last partly broken away and in section showing a shoe in place thereon and in section, the last and the shoe being in lasting position.

Fig. 3 is a cross-sectional view taken on line 3—3 of Fig. 2.

In accordance with the invention the fore part of the last is made solid and integral with a rigid supporting base whereby the last may be supported in lasting and vulcanizing machines, and the rear portion of the last is pivotally mounted thereon and arranged for arcuate movement with relation to the fore part and base for releasing the shoe, such arcuate movement being in a direction to facilitate the removal without damage to the shoe.

Referring to the drawing, the numeral 10 designates a solid rigid base of rectangular form, and the numeral 11 designates the fore part of a last integral therewith, the sole of the last being away from the base. The rear or heel portion of the last 13 is mounted on a lever 14 pivoted at 15 to the base of the last. The fore part and rear portion of the last are fitted to swing relatively and arcuately about the pivot 15, their surfaces 16 and 17, which may be in sliding contact, being concentric with the pivot and their arc of contact being such as to intersect the shank region of the shoe forward of the heel portion and its axis of rotation being below and well to the rear of the toe of the last, and preferably below the ball region of the last, or below a position of the

sole forward of the ball region, so that when the lever 14 is swung upwardly as in Fig. 1 the length of the last along the sole is substantially decreased to facilitate removal of the shoe.

5 To facilitate support of the heel portion of the last in lasting position a supporting shoulder 18 may be provided on the fore part of the last by grooving the arcuate surface thereabove, and a key 19 on the rear or heel portion is adapted to 10 slide in the groove and rest against the shoulder.

The lever 14 is bifurcated so as to engage the pivot pin 15 at opposite sides of the base of the last and to clear the last support, and has a handle 20 for manipulating it in its pivoted movement. In its lowered position the lever 14 rests on the base and supports the heel portion 13 of the last in assembled position, as shown in Fig. 2.

For heating the last during the vulcanizing operation, the forepart of the last has steam passages 21 formed therein and connected to inlet and exhaust openings 22, 23 in the base 10 and the heel portion 13 of the last is similarly formed with heating passages 24 connected to inlet and exhaust openings 25, 26 on the lever 14. These openings may be connected to flexible conduits at the vulcanizing station to circulate steam or other heating fluid therethrough. The steam passages 24 may conveniently be formed by drilling intersecting bores 30, 31, 32 in the body of 30 the last and closing the bores at the surface of the last as by plugs 33, 34, 35.

In using the last, the heel portion of the last is swung about the pivot 15 to the position shown in Fig. 1 and the shoe is slipped over the last to 35 the position shown in full lines. The heel portion is then lowered by the operator by means of the handle 20, the shoe being pressed downwardly at the heel. The pivotal movement of the heel portion acts to draw the shoe onto the last during this operation. The sole may then be vulcanized by heat supplied to the last, and if desired, pressure may be applied along the sole.

When removing the shoe, the handle 20 is 40 grasped by the operator and lifted. This movement loosens the last and withdraws it from the toe of the shoe without bending the sole thereof and the shoe may then be removed by a movement of its heel portion upwardly and forwardly toward the toe of the last. The last is especially 45 effective in avoiding damage to shoes where the sole is freshly vulcanized and lacks strength due to its heated condition.

Variations may be made without departing from the scope of the invention as it is defined by the following claims.

I claim:

1. A last for footwear, said last comprising a base, a last member integral therewith, and a second last member pivotally secured to said base and slideable with respect to the first-named last member, said last members providing a sole supporting surface separable at the shank region of the last by the pivotal movement of said second last member.

2. A last for footwear, said last comprising a base, a last member shaped to the fore part of the shoe and integral with said base and overhanging the same, a heel member arcuately slideable with respect to said last member and providing a continuation of its shoe supporting surface separable therefrom at the shank region of the last, said heel member having a portion pivotally mounted on said base for guiding said heel member in its arcuate movement.

3. A last for footwear, said last comprising a toe member and a heel member slideable arcuately with respect to each other along a path of

revolution intersecting the shank portion of the last substantially at the breast of the heel and having its axis transverse of the last, a base integral with the toe member, and an arm pivoted on said base at the axis of said path and adapted to guide said heel member in an arcuate movement with respect to said toe member.

4. A last for footwear, said last comprising a toe member and a heel member, said members having cooperating surfaces of revolution movable with relation one to the other, said surfaces intersecting the last substantially in the region of the breast of the heel and extending rearwardly and away from the sole of the last so that the fore and aft dimension of the heel member at the sole surface is greater than at any plane parallel thereto, a base for supporting said toe member and an arm pivoted to said base at the axis of said surfaces and supporting said heel member.

FRANK J. MACDONALD.
